SPRAYING APPARATUS FOR SHOE
SOLE MARGINSMieth Maeser, Beverly, Mass., assignor to United
Shoe Machinery Corporation, Flemington, N. J.,
a corporation of New Jersey

Application January 3, 1951, Serial No. 204,137

7 Claims. (Cl. 118—301)

1

This invention relates to spraying apparatus and is illustrated as embodied in a device for spraying ink on the peripheral face and adjacent margin of the sole of a shoe.

In the finishing of shoe soles by the application of a colored liquid, hereinafter called ink, thereto, it is customary to apply the liquid largely by hand, as by the use of an ordinary tooth brush. Numerous devices have been provided for applying the liquid mechanically but difficulty has been found with such devices in restricting the material strictly to the surfaces to be coated with the result that many pieces of work have been spoiled and hand work is still largely in vogue.

It has been proposed to employ spraying apparatus for applying the ink on such work. One difficulty inherent in such an apparatus results from the force in which the particles of spray contact the work with the result that a certain proportion of the particles bounce from contact with the work and soil the adjacent portion of the apparatus as well as daubing the work.

Accordingly, an object of the invention is to devise an improved apparatus which will avoid these difficulties and allow the operator to present pieces of work rapidly and continually.

To this end a feature of the invention resides in an arrangement of the spraying apparatus such that a spray gun is contained within a casing but in spaced relation to the walls thereof and in providing means for exhausting the air from such casing so that surplus particles are drawn back away from the outlet of the apparatus and not allowed to soil either the work or the outer surfaces of the casing.

Another feature of the apparatus resides in a work-protecting slide positioned to move transversely of the outlet in engagement with one corner of the work. As herein illustrated, the guides for this slide are also utilized as guides for the work and are provided with terminal surfaces against which the periphery of a sole may be pressed as it traverses the outlet of the apparatus.

These and other features of the invention will best be understood from the following specification when taken in connection with the accompanying drawings, in which

Fig. 1 is a side elevation of the apparatus;

Fig. 2 is a detail section through the control valve on the line II—II of Fig. 1;

Fig. 3 is a section taken transversely of the slide on the line III—III of Fig. 1;

Fig. 4 is a rear elevation of part of the apparatus, showing also a supply receptacle;

Fig. 5 is a horizontal section on the line V—V of Fig. 6;

2

Fig. 6 is a vertical section through the center of the spray passages taken in a plane parallel to the plane of Fig. 1; and

Fig. 7 is an enlarged section on the line VII—VII of Fig. 1 through the spraying apparatus taken in a plane normal to the plane of Fig. 6.

This spraying apparatus is shown as mounted upon a base 10 which may be part of the bench or part of a pedestal and comprises a post 12 having an offset arm 14 in which there is a spacing bolt 16 swingably supporting a control valve 18, to be later described.

Also attached to the post and swingable upon a stud 20 is an arm 22 to which there is attached 15 by screws 24 a spraying apparatus 26. This spraying apparatus comprises a two-part casing 28, 30 with the parts held together with screw studs 32. In the casing part 28 there is a cylindrical passage 34 (Fig. 6) having an upper enlarged portion 36 with a shoulder 38 interposed 20 between the two. The top of the portion 36 is closed by a screw cap 37.

Set into this casing and spaced from the walls of the portion 34 is a spray gun 40 having an enlarged head 42 which substantially fits the portion of the casing above the shoulder 38 and rests upon that shoulder, against which it is clamped by a screw ring 44. The head 42 has vertical grooves 43 (Fig. 5) in its periphery and these, 25 with the wall of the enlarged portion 36 form exhaust passages for a purpose to be later described. Disposed upon a vertical axis in the spray gun 40 are Venturi passages 46, 48 closed at the top by a screw 50 and having an air inlet port 52 supplied with air at 5 lbs. pressure per square inch through a passage 54 (Fig. 5) in a nipple 55 screwed in the side of the casing 28 and having a reduced inner end which fits in the inlet port 52.

40 Liquid is supplied at the reduced mid-portion of the Venturi passages 46, 48 by way of another port 60 (Fig. 7) and through a passage in a sleeve 62 (Fig. 6) fitting in a neck 64 in the side of the casing. The outlet of the sleeve 62 is controlled 45 by a needle valve 66 urged inwardly by a spring 68 to close the outlet in a cap plate 70. Liquid is supplied to the passage of the sleeve 62 through a lateral inlet opening 74. To this inlet liquid is supplied through a conduit 76 (Figs. 4 and 5) held in the neck 64 by a compression fitting 78 and with its other end dipping in a receptacle 80 (Fig. 4).

50 To support the receptacle, an angle iron 80 is attached to the base 10 by screws 92 and a cover plate 82 for the receptacle is fastened on the angle iron by nuts threaded on the reduced upper

ends of depending hexagonal rods 88. A cross bar 86 is secured to the lower ends of the rods 88 and in this cross bar is threaded a hand screw 84 pressing against the bottom of the receptacle to clamp it against the cover plate 82.

Air under pressure delivered to the receptacle 80 through a conduit 94 pushes the liquid up through the conduit 79 into the inlet 74 in the neck 64 of the spray apparatus as air under low pressure is delivered to the inlet port 52 through the nipple 55 (Fig. 5), the inner end of which fits in the enlarged head 42 of the spray gun thus causing the liquid to be driven from passage 48 as a spray. This head 42 is held against rotation by means of a setscrew 98, so that its inlet ports 52 and 60 will align with the supply sleeves.

The lower portion 30 of the casing of the spray apparatus has a cylindrical rim 100 fitting over a depending neck 102 on the upper portion. The rim adjoins a tapered passage 104 corresponding to but larger than the tapered outlet end 106 of the spray gun. The tapered passage 104 adjoins a cylindrical vertical outlet passage 108 formed as a surface of revolution about a vertical axis and terminating in a delivery opening 110 which is formed by the intersection with the passage 108 of an inclined surface 112 on the casing portion 30.

Against this inclined surface 112 there rests a slide 114 with guide ribs 115 which are received between shouldered side plates 116 and 118 (Fig. 3), the end surfaces 120 (Fig. 1) of which are positioned opposite to about the mid portion of the outlet. These surfaces 120 serve as guides for the periphery of the sole 122 of a shoe S. The outer side 124 of the casing portion 30 projects into the crease C of the shoe thus cooperating with the guide surfaces 120 to guide the upper margin 126 of the sole as well as its periphery 128 in line with the spray issuing from the delivery opening 110.

The slide 114 has an end surface 130 (Fig. 6) which bears against the bottom corner of the periphery of the sole to prevent the sprayed liquid from passing around that corner onto the bottom of the shoe and inasmuch as the slide 114 is urged downwardly by a spring 134 its position is determined by the thickness of the sole and the width of the extension thereof. The upper end of the spring 134 bears against a cap plate 136 held to the side plates 116, 118 by screws. To insure a close contact between the slide and the inclined surface 112, a spring 140 (Figs. 1 and 3) is provided which bears against the lower surface thereof, this spring being wrapped around a stud 142 carried by the side plate 118.

Because of the importance of preventing the ink from being spread beyond the limits of the area to be coated, as when the uppers are light colored, and to eliminate the difficulty due to spattering and the like, the upper chamber 36 of the casing 28 has an exhaust passage 150 in which fits a sleeve 152 (Fig. 7) having a Venturi passage 154 at the smallest part of which openings 156 are provided through which there will be drawn in the air and spray contained in the chamber 36. Air under about 10 lbs. pressure per square inch is delivered to this Venturi passage through a flexible conduit 158 and, if desired, a waste conduit 160 may be installed at the end of the Venturi tube. In this as well as in the spray gun a plain arrow has been used to indicate the flow in an air passage and a feathered arrow to indicate a flow of mixed air and liquid.

The flexible conduit 158 and a similar conduit 75

162 supplying air to the spray gun inlet passage 54 are joined to the casing 164 (Fig. 1) of the control valve 18. On the opposite side of this casing (Fig. 1) are similar conduits 166, 168 leading from the source of supply (not shown). Within the casing 164 is a slide 170 having lands spaced to be opposite to the supply pipes and passages such as that at 172 which permit the flow of air from the supply pipes to the delivery pipes 158, 162. Because of the shorter land opposite to the conduit 158 air under pressure will be supplied to the ejector Venturi sleeve 152 before it is supplied through the pipe 162 to the spray gun thus insuring an exhaust suction before liquid is drawn into the spray gun. The slide 170 is pivotally connected to a lever 174 which swings upon a stud 176 on the post 12 and has a clamp member 178 joining it to a treadle operated rod 180 under the control of the operator.

The admission of liquid to the spray gun is also operator-controlled by this same treadle rod 180 which is connected to the valve rod 66 (Figs. 1 and 6) by means of a two-part bell crank 182, the lower part of which is split and clamped on the hub 184 of the forked upper part 186 positioned to engage a nut 188 on the treadle rod. Movement is imparted to the bell crank 182 by a collar 190 on the treadle rod 180 which engages the upper face of the bell crank 182 as the treadle rod is depressed. By suspending the valve 18 on the spacing bolt 16 there can be no binding of the slide 170 in the casing 164 as the end of the lever 174 moves in an arcuate path.

It will be noted that the position of the spray gun and its casing 28, 30 may be adjusted to suit the operator by loosening a stud 192 passing through a slot 194 in the post 12, this stud being threaded in the arm 22 which carries the spray gun.

In the operation of the machine the sole of a shoe will be presented to the delivery opening 110 so that its periphery contacts with the ends 120 (Fig. 6) of the guide plates 116, 118. In so doing the slide 114 will be pressed back while remaining in contact with the bottom corner of the sole. At the same time the upper of the shoe will rest against the surface 124 of the nozzle and will be protected thereby while the margin or extension of the sole is exposed to the spray.

Then, as the operator depresses the treadle connected to the treadle rod 180, he will open up the air supply to the exhaust passing through the conduit 158 and the air supply to the spray gun passing through the conduit 162 and will draw back the needle valve 66 which controls the supply of liquid to the spray gun. The shoe will then be turned to present successive portions of the periphery of the sole to the apparatus. In so doing, a sharp margin will be determined partly by the parts at the delivery opening 110 and partly because any surplus spray will be drawn up through the annular passage surrounding the spray gun and through the grooves 43 in the enlarged head portion thereof to be sucked in through the openings 156 of the Venturi passage in the sleeve 152 and thence out through the disposal pipe 160.

Having thus described my invention, what I claim as new and desire to secure by Letters Patent of the United States is:

1. In a spraying apparatus, a standard, a spray nozzle thereon pointed down, a casing surrounding said spray nozzle and provided with an outlet opening in alignment therewith, means

outside the opening for guiding a shoe with its sole extension beneath said outlet opening including a movable guard contacting the bottom corner of a sole extension to protect the bottom of the shoe, and means connected to said casing above said nozzle for producing suction in said casing to draw back surplus spray.

2. In a spraying apparatus, an annular casing closed at one end, a spray nozzle supported within said casing and spaced therefrom to provide a passage surrounding the end of the nozzle, said spray nozzle having a longitudinal passage, a supply pipe for liquid extending through said annular casing and terminating in said passage, means for supplying air under pressure to said passage, suction exhaust means connected to the closed end of said casing, said casing being provided with an outlet opening adjacent to the end of the nozzle and in alinement therewith, and a work-engaging shield slidably mounted on said casing for movement across said outlet opening.

3. In a spraying apparatus, a casing having an outlet opening, said casing being provided with a tapered inner surface adjacent to said outlet opening and with a substantially cylindrical inner surface adjoining said tapered surface, a shoulder around said cylindrical surface, a spray gun comprising a cylindrical portion fitting said inner surface and having lengthwise grooves along its periphery, and a tapered nozzle portion, means for gripping said cylindrical portion against said shoulder thereby securing the tapered portion in spaced relation to the tapered portion of the casing, means for exhausting air from said casing through the grooves in the cylindrical portion, and means traversing said casing to supply liquid and air to said spray nozzle.

4. In a spraying apparatus, a casing having an outlet opening, means for delivering a spray to said opening, said casing having an outer surface inclined to the direction of the spray, and a work-displaceable slide mounted to move along said outer surface until it partially covers said outlet opening, the end of said slide having a work-engaging spray-control surface which is substantially parallel to the direction of the spray.

5. In a spraying apparatus, a casing having an outlet opening, means for delivering a spray to said opening, said casing having an outer surface inclined to the direction of the spray, a work-displaceable slide plate movably mounted on said outer surface for partially covering said outlet opening, the end of said slide having a work-engaging surface substantially parallel to

the direction of the spray, and guides for the edges of said slide having terminal surfaces substantially normal to the inclined surface of the casing and serving as work-engaging guides whereby adjacent angularly disposed surfaces of a piece of work, one of which rests against said guide terminals, may be treated by said spray.

6. In a spraying apparatus, a casing having an outlet passage formed as a surface of revolution, a spraying device in alinement with the axis of said surface, the outer surface of said casing adjacent to said outlet being inclined to the axis of the passage and providing at one side a tapered projecting portion adapted to be received in the crease of a shoe having an attached sole thus exposing a portion of the sole adjacent to said crease to the spray, and a slidably arranged, spring-impelled guard mounted for movement across said passage for engagement with the bottom corner of the sole of a shoe which is positioned by said projecting portion, regardless of its thickness, whereby the spray may be applied to the whole of the edge of the sole as the margin of its upper surface is also being coated.

7. In a spraying apparatus, a casing having a passage terminating in an outlet opening, the outer faces of said casing being both inclined to the axis of said passage and meeting to provide a sharp edge adjacent to one side thereof for reception in the crease of a shoe, guides on said casing adjacent to said outlet opening and terminating beside a mid portion thereof, and a spring-pressed slide in said guides having an end surface movable across the axis of said opening, said surface being adapted to be engaged by the bottom corner of the sole to protect the bottom surface thereof from being coated.

MIETH MAESER.
